(57) **CLAIM**

The ornamental design for a defibrillator as shown and described.

DESCRIPTION

FIG. 1.1 is a top, front and left side perspective view of the defibrillator showing my design;

FIG. 1.2 is a front elevational view thereof;

FIG. 1.3 is a rear elevational view thereof;

FIG. 1.4 is a right elevational view thereof;

FIG. 1.5 is a left elevational view thereof;

FIG. 1.6 is a top plan view thereof; and

FIG. 1.7 is a bottom plan view thereof.

The broken lines illustrate portions of the defibrillator and forms no part of the claimed design.
